UNITED STATES PATENT OFFICE.

WILLIAM F. CHRISTISON AND HADLEY O. CHRISTISON, OF KOKOMO, INDIANA.

WIRE-NAIL MACHINE.

1,242,522.

Specification of Letters Patent.

Patented Oct. 9, 1917.

Application filed December 16, 1916. Serial No. 137,438.

To all whom it may concern:

Be it known that we, WILLIAM F. CHRISTISON and HADLEY O. CHRISTISON, citizens of the United States, residing at Kokomo, 5 in the county of Howard and State of Indiana, have invented certain new and useful Improvements in Wire-Nail Machines, of which the following is a specification.

The object of this invention is to simplify 10 the construction of a wire-nail making machine by reducing the number of parts, making it operative with less friction and wear, less expensive to construct and afterward to maintain and easier to operate, without decreasing the volume or quality of the output 15 from it.

We accomplish the above and other objects which will hereinafter appear, by the mechanism illustrated in the accompanying 20 drawings, in which—

Figure 1 is a top plan view of our invention showing the parts positioned to point and cut off an otherwise finished nail. Fig. 2 is a vertical section on the line 2—2 of 25 Fig. 1 and Fig. 3 is a vertical section on the line 3—3 of Fig. 1.

Like characters of reference indicate like parts throughout the several views of the drawings.

The table or plate 4, its legs or standards 5, and the hangers 6, secured to the under- 30 side of the table, constitute the framework of the machine. In suitable journals 7, on top of the table turns the shaft 8, carrying a fly-wheel 9, and an adjacent tight pulley 10 and loose pulley 11. At the other end of the shaft is a crank-wheel 12 having a diametrical slideway in which a crank-pin 13 is adjustably held, the adjustment being 35 toward or from the axis of rotation of the shaft to vary the length of the crank-arm. Fulcrumed to the top of the table is a lever 14, the free end of which is connected by a pitman rod 15 with trunnions on a sleeve 40 15 on the crank-pin 13. A suitably expanded portion of the lever forms a support for a pair of wire-gripping wheels 16, 16, mounted in the heads of rods 17, 17, oblique to each other as shown in Fig. 1. The lever 45 has perforated ears 18, 18, which guide the rods 17. Springs 19, 19, wrapped around the respective rods and bearing against the

head at one end and ear at the other force the wheels 16, 16, together with an elastic gripping tension. A wire 20, from which 55 the nails produced by the machine are made, is gripped between the pair of wheels when the lever is swung toward the shaft 8, and the wheels automatically release their grip when the lever swings the other way. 60

As the wire 20 is usually fed to the machine from a round coil, it is first straightened by passing between two rows of wheels 21 which contact the wire in the usual manner for straightening purposes. 65

The wire is fed through a suitable hole in an anvil 22, supported by the table on the opposite side of lever 14 from wheels 21 by engagement between the gripping wheels 16 at each oscillation of the lever. The anvil has a vertical dove tail groove on its side remote from lever 14 in which a block 23 is adjustably seated. The block has a hole in line with that of the anvil for the wire to pass through, and on its outer face it is 70 formed with a dove tail groove at right angles to the groove in the anvil in which the block is seated. A pair of clamping members 24 and 25 is seated in the groove of the block. The member 24 is fixed while the 75 other member 25 has a reciprocating movement whereby it is moved to clamp the wire 20 against the member 24 while a nail-head is being formed. The two members 24 and 25 securely hold the wire from slipping 80 while the head of the nail is made by fulfilling the end of the wire in a shaping cavity in the members at the joint between them, by the pressure of a reciprocating hammer 85 26. Clamping pressure is applied to the 90 outer end of the member 25, through a push-bar 27, one end of which is seated in a socket in the end of member 25, and the other end bears against and is fastened to the short arm of a pivoted lever 28, pivoted at 29 to the table 4. Withdrawal of the member 25 is by a wire 30 connecting the member with lever 28, being preferably fastened to a tightening device 31 on the lever by which the wire is maintained in a taut 95 condition. The lever 28 is normally moved by a spring 32 in a direction to draw the member 25 out of clamping engagement with the wire 20. The end of the long arm of 100

lever 28 carries a friction wheel 33 which is also held by the tension of spring 32 against the cam-shaped side of a disk 34 mounted on the shaft 8. The low place occurs on the cam where it is desired to release the lever 28 and consequently the clamping pressure of member 25 against the wire 20 while the latter is being fed the length of a nail. The high place occurs while the nail is being pointed and cut off and a head formed on the new end of the wire from which the nail was cut.

The hammer 26 which fills the metal to form the head of the nail is removably seated in a sliding block 35. The latter is directed by ways 36 from the table. A crank rod 37 connects the block with a crank in the shaft 8, set to bring the hammer against the end of wire 20 while the latter is held by the clamping members 24 and 25.

The nail is then simultaneously pointed and cut off by a pair of chisels 38 which reciprocate on diametrically opposite sides of the wire 20. The point is formed by the shapes of the cutting ends of the two chisels which pinch off the wire between them. The chisels are mounted in heads 39, in horizontal dove tail grooves therein and are adjusted by set screws 40. The heads are removably mounted in slots in the upper ends of vertical levers 41, 41, as shown and are held there by removable cap plates which enable shims to be inserted or removed to raise or lower the chisels. The levers 41, 41, are pivoted on rods 42, 42, which are supported by the hangers 6, 6. The levers are separated from each other as shown to provide unobstructed room for the nail before it is cut off and for its discharge afterward. They extend through a slot 43 in the table and are connected at their lower ends by a spring-tie 44. The nail, after it is cut off, drops by gravity through the slot 43, and is carried away by any usual and suitable means, not shown.

The levers 41, 41, are moved toward each other to cause their chisels 38, 38, to point and sever the nail by wedges 45, 45, respectively. These wedges slide in ways 46 on the table 4, and are reciprocated therein by connection through rods 47 having suitable openings, with eccentrics 48, on shaft 8. To reduce the friction between the levers and their wedges we prefer to interpose friction rollers 49, and because the swinging movement of the levers would impart a lateral or skidding movement to the rollers if the latter were mounted on the former, we prefer to mount the rollers in heads 51 on the ends of bars 50, resting upon the table and pivoted at ends remote from the heads to the table. The heads 51 may bear against the levers 41, directly, but we prefer to interpose pin-bearings as shown in Fig. 2. As there shown, sockets are provided in heads

51, in which pins 54 are pivoted at one end and the other bears against the adjacent lever entering indents therein to keep them positioned.

While we have described our invention with more or less minuteness as regards details of construction and arrangement and as being embodied in certain precise forms, we do not desire to be limited thereto unduly or any more than is pointed out in the claims. On the contrary we contemplate all proper changes in form, construction and arrangement, the omission of immaterial elements and the substitution of equivalents as circumstances may suggest or as necessity may render expedient.

We claim—

1. In a wire nail machine, means for pointing and cutting off the nail, comprising a pair of pivoted levers swinging in a vertical plane at right angles to the wire, chisels carried by the levers, reciprocating wedge means to swing the levers toward the wire, a pair of bars one for each of said swinging levers, each bar having a head, said head being assembled between the lever and an adjacent wedge, said bar being pivoted, and a friction roller in the head contacting the wedge.

2. In a wire nail machine, means for pointing and cutting off the nail comprising a pair of pivoted levers swinging in a vertical plane at right angles to the wire, chisels carried by the levers, horizontally reciprocating wedge means to swing the levers toward the wire, a roller to reduce the anti-friction between each wedge and adjacent lever, and means for movably supporting the roller independently of said wedge and lever.

3. In a wire nail machine, a rotating shaft, an anvil, wire feeding means, wire clamping means, and nail-head forming means, all of said means operated from said shaft, in combination with a pair of pivoted levers swinging in a vertical plane at right angles to the wire, elastic means to normally separate the upper ends of the levers, chisels carried by the levers, horizontal guides, wedges directed by said guides to move the upper ends of the levers toward each other, means comprising eccentrics on said shaft for reciprocating the wedges and anti-friction wheels between the wedges and levers said wheels having oscillatory movement.

4. In a wire nail machine, a rotating shaft, an anvil, wire feeding means, wire clamping means, and nail-head forming means, all of said means operated from said shaft, in combination with a pair of pivoted levers swinging in planes at right angles to that of the wire, chisels carried by the levers, elastic means to normally separate the upper ends of the levers, guides, wedges directed by said guides to move the upper ends of

the levers toward each other, means comprising eccentrics on said shaft for reciprocating the wedges, a head between each wedge and lever, said head having oscillatory movement, an anti-friction wheel in the head contacting the wedge and pin bearings between the head and lever.

5 In witness whereof, we have hereunto set

our hands and seals at Kokomo, Indiana,
this 7th day of December, A. D. one thou- 10
sand nine hundred and sixteen.
